UNITED STATES PATENT OFFICE.

CHARLES E. KISTNER, OF CINCINNATI, OHIO.

DESIGN FOR A REFLECTOR FOR AUTOMOBILE LIGHTS.

Application filed June 1, 1923. Serial No. 6,371. Term of patent 14 years.

To all whom it may concern:

Be it known that I, CHARLES E. KISTNER, a citizen of the United States, residing at the city of Cincinnati, in the county of Hamilton and State of Ohio, have invented a new, original, and ornamental Design for Reflectors for Automobile Lights, of which the following is a specification, reference being had to the accompanying drawing, forming part thereof.

Fig. 1, is a plan view of a reflector for automobile lights showing my design, and

Fig. 2, is a cross section of the reflector taken on the line 2—2 of Fig. 1, to show more clearly my new design.

I claim:

The ornamental design for a reflector for automobile lights, as shown.

Witness my hand at the city of Cincinnati, county of Hamilton, and State of Ohio, this 29th day of May, 1923.

CHARLES E. KISTNER.
